UNITED STATES PATENT OFFICE

2,586,642

ELECTRIC ALARM CLOCK

William P. Gallagher, Chicago, Ill., assignor to
 International Register Company, Chicago, Ill.,
 a corporation of Illinois

Application June 7, 1946, Serial No. 675,103

6 Claims. (Cl. 58—38)

1

My invention relates, generally, to clocks and it has particular relation to improvement in electric alarm clocks for household use. The present invention is an improvement over the clock disclosed and claimed in my copending application Serial No. 640,245, filed January 10, 1946, and assigned to the assignee of this application, now Patent No. 2,491,103, issued December 13, 1949.

Among the objects of my invention are: to provide an electric alarm clock that is simple and efficient in operation and which can be manufactured readily and economically; to operate the alarm by a rotatable member which is driven by the motor that also drives the time indicating mechanism; to employ a plurality of actuating sections on the member driven by the motor and arrange the same so that each swings a hammer to strike an alarm bell during each revolution of the member; to provide the actuating sections in the form cam surfaces on a cam mounted for rotation with the motor rotor on its shaft; to mount the hammer so that it swings freely when it strikes the bell and is undamped by the operating cam; to support the hammer on a light weight resilient yoke to reduce the damping effect thereof; to support rockably the yoke carrying the hammer on the time setting shaft; to arrest the yoke and hammer between the bell and the cam in the non-operative position; to release the yoke from the non-operative position by mechanism driven by the motor; and to provide for manually controlling the release from the non-operative position.

Other objects of my invention will, in part, be obvious and in part appear hereinafter.

Accordingly, my invention is disclosed in the embodiments thereof shown in the accompanying drawings and it comprises the features of construction, combination of elements and arrangement of parts which will be exemplified in the construction hereinafter set forth and the scope of the application of which will be indicated in the appended claims.

For a more complete understanding of the nature and scope of my invention reference may be had to the following detailed description, taken together with the accompanying drawings, in which:

Figure 1 is a view, in front elevation, of a clock in which my invention is incorporated;

Figure 2 is a view, in rear elevation, of the clock shown in Figure 1;

Figure 3 is a view, in rear elevation, of the clock shown in Figure 1, the back plate having been removed and a portion of the motor casing

2

being broken away in order to illustrate the details of construction;

Figure 4 is a view, similar to Figure 3, but showing the bell hammer support yoke held in the non-operative position by the manually operable alarm release shaft;

Figure 5 is a sectional view, at an enlarged scale, taken along the line 5—5 of Figure 4;

Figure 6 is a detail view, at an enlarged scale, of the bell hammer support yoke and the motor driven automatic release mechanism therefor;

Figure 7 is a detail sectional view, taken along the line 7—7 of Figure 6;

Figure 8 is a view, similar to Figure 6, but showing the bell hammer support yoke and hammer in the non-operative position;

Figure 9 is a detail sectional view taken along the line 9—9 of Figure 8;

Figure 10 is a perspective view of the bell hammer support yoke and the hammer carried thereby;

Figure 11 is a view illustrating, schematically, the gear train interconnecting the motor and the time indicating mechanism and also illustrating the cam driven by the motor and the manner in which the alarm can be set; and

Figure 12 is a view, in side elevation, of the manually operable alarm release shaft.

Referring now particularly to Figures 1 and 5 of the drawings, it will be observed that the reference character 10 designates a clockcase which may be formed of any suitable material, either metal or plastic or the like. A transparent curved cover 11 is secured by a ring 12 in a circular recess 13, that is formed in the front wall of the case 10. A face 14 can be viewed through the transparent cover 11 and it carries the numerals 1 through 12 to indicate the hours. A scale 15 divides the hours into suitable subdivisions such as quarter hours. Conventional minute and hour hands 16 and 17 are arranged to cooperate with the numerals on the face 14.

As will appear hereinafter, in more complete detail, the present clock construction embodies an alarm mechanism. For the purpose of indicating the time at which the alarm mechanism is set to operate, an alarm set hand 18 is mounted for rotation coaxially with the hands 16 and 17 relative to the numerals on the face 14 and to the scale 15.

The face 14 is provided with an aperture 19 through which an indicator 20 can be viewed to determine whether the clock motor is in operation. The indicator 20 is mounted to rotate eccentrically in the aperture 19 or with respect to

the aperture 19 for the purpose of increasing the effectiveness of the indication given thereby.

Reference will now be had to the schematic layout shown in Figure 11 of the drawings for the purpose of describing at the outset the relationship of certain of the mechanisms embodied in the clock construction. It will be noted that the minute hand 16 is mounted on and for rotation with a shaft 24 and that the hour hand 17 is similarly mounted on sleeve 25 which is positioned around the shaft 24. A pinion 26 is secured to the shaft 24 while a gear wheel 27 is secured to the sleeve 25. The pinion 26 meshes with a gear wheel 28 while the gear wheel 27 meshes with a pinion 29 that is mounted for rotation with the gear wheel 28. The gear reduction is such that the shaft 24 and the minute hand 16 rotate 12 times for each revolution of the hour hand 17 and sleeve 25.

The gear wheel 28 and pinion 29 are commonly driven by a pinion 30 which may be driven through a clutch 31 of the kind disclosed in my copending application Serial No. 656,953, filed March 25, 1946, now Patent No. 2,564,103, issued August 14, 1951 by a gear wheel 32. The pinion 30 is mounted for rotation with a time setting shaft 33 to which is secured a time setting knob 34. The clutch 31 is provided to permit the setting of the time as indicated by the hands 16 and 17 without requiring rotation of the gear wheel 32 and the gear train in the mesh therewith which connects the same to the driving motor.

The gear train just referred to comprises a series of intermeshing pinions and gear wheels 36 through 47, the pinion 36 meshing with the gear wheel 32 and the gear wheel 47 meshing with a pinion 48 that is mounted on and driven by a motor shaft 49 which carries a rotor 50 of a synchronous motor of suitable construction such as that shown in Haydon Patent No. 2,353,305. It will be understood, however, that other suitable types of motors can be employed for operating the clock mechanism disclosed herein. The construction of the motor is such that the rotor 50 is caused to rotate at a speed of 450 R. P. M. when the motor is energized with alternating current at a frequency of 60 cycles per second.

Mounted on the motor shaft 49 is a cam 51 which is employed for operating the alarm mechanism. The cam 51 is illustrated diagrammatically only in Figure 11. Its shape and function will be described in more detail hereinafter.

With a view to providing for adjusting the position of the alarm set hand 18 it is mounted on an alarm hand gear hub 56 which in turn is positioned for rotation coaxially with the shaft 24 and the sleeve 25. An alarm set gear wheel 57 is secured to the hub 56 and is arranged to be driven through an idler gear wheel 58 by a pinion 59. The pinion 59 is mounted on an alarm set shaft 60 which can be manually moved by an alarm set knob 61.

In Figures 3, 4 and 5 of the drawings the motor, referred to hereinbefore, is indicated, generally, at 64. It includes a case or cover 65 which surrounds the rotor 50 and which may be secured as by a press fit over shading rings 66 which are carried by a core structure or motor frame 67 that forms a part of the magnetic circuit of the motor as is more fully set forth in the patent to Haydon previously referred to. The case or cover 65 has a circular aperture 68

through which the motor shaft 49 projects for carrying the cam 51.

The gear train, previously described, is located within a gear case 69 on which the motor 5 is mounted and which may be secured, as by screws 70, to the rear wall of a cup-shaped base plate 71 which has a flange 72 that interfits with the flange 73, integrally formed with the case 10 to hold the mechanism in place therein. Pillars 74 extend rearwardly from the base plate 71 to a back plate 75, Figure 2, where they are secured thereto as by screws 76.

Also mounted on the rear of the base plate 71 is a Z-shaped bell mounting bracket 80. It may be secured thereon by any suitable means such as by screws 81. A bell 82 is mounted on the bracket 80 by a centrally located screw 83. The bell 82 may be formed of annealed yellow brass. As indicated in Figure 2 apertures 84 are provided in the back plate 75 in front of the bell 82 so that the tone thereof will not be muffled as would otherwise be the case if the back plate 75 completely enclosed the rear of the case 10.

The bell 82 is arranged to be repeatedly struck by a tip 86 of a hammer 87 which may be formed of brass. The hammer 87 is carried by a bifurcated bell hammer support yoke, indicated generally at 88, in Figure 10 of the drawings. The yoke 88 is preferably formed of resilient material such as Phosphor bronze. Its arms 89 and 90 are apertured as indicated at 91 and 92 for mounting on the time set shaft 33, as is illustrated more clearly in Figure 5 of the drawings. It will be understood that the yoke 88 can be mounted on a shaft, other than the time set shaft 33, this shaft being chosen for its pivot support in order to take advantage of its presence and obviate the necessity for providing a separate shaft for this purpose.

Referring again to Figure 10 it will be observed that the arm 89 of the yoke 88 is fork shaped and includes a hammer supporting section 93 a part of which interfits with a slot 94 in the hammer 87 and which has an offset portion 95 to bring the same above the outer surface of the hammer 87. The hammer 87 is secured to the section 93 by suitable means such as a single hollow rivet 96. This construction permits the fastening of the hammer 87 to the yoke 88 by a single rivet or fastening device 96 since this together with the slot 94 and the associated portion of the section 93 serve to hold the hammer 87 rigidly in place.

The arm 89 also includes a cam striking section 97 which, as illustrated, is relatively long and narrow. It is offset intermediate its length as indicated at 98 and has an inwardly turned end portion 99 that is arranged to be engaged successively by surfaces 100 of points 101 of the cam 51 which, it will be recalled, is mounted for rotation with the motor shaft 49.

It will be noted that the cam 51 comprises a three point operating member having a plurality of operating surfaces 100, each of which is arranged to strike the inturned end portion 99 of the cam striking section 97 for the purpose of rocking the yoke 88 in a counter-clockwise direction, as viewed in Figure 6, so that the tip 86 of the hammer 87 will strike the bell 82 a blow and cause the same to vibrate. It has been found that exceptionally satisfactory results are obtained when the cam 51 or operating member has three points 101 each of which strikes the cam striking section 97 during each revolution of the rotor 50. When the rotor 50 operates at a speed of 450 R. P. M., the hammer 87 is caused to

impact the bell 82 about 1350 times each minute. The arrangement of the yoke 88 and the cam 51 is such that when the tip 86 of the hammer 87 strikes the bell 82, the inturned end 99 of the cam striking section 97 is out of contact with the particular cam surface 100 which has caused the movement of the yoke 88. Thus the hammer 87 is swinging substantially freely when it strikes the bell 82 and the tone thereof is substantially undamped. If means, such as the cutoff lever 110 acting against cut-out arm 108 extending from the yoke 88 as described hereinafter, were not provided for holding the cam striking section 97 out of the path of the points 101 of the cam 51, the hammer 87 would continue to strike the bell 82. As will presently appear, means are provided for releasing the yoke 88 for operation by the cam 51 only at a predetermined time and the extent of the operation is under the control of manually operable means which serves to shut off the alarm.

Referring again to Figure 10 it will be noted that the arm 90 is also fork shaped and comprises a side movement limiting section 105 which, as illustrated more clearly in Figure 6, bears against the outer surface of the core structure or motor frame 67 and limits the extent of clockwise movement of the yoke 88. The arm 90 also includes a section 106 having a hold down lug 107 the surface of which is convex and which, as indicated in Figure 5, bears against the surface of the shading ring 66 to prevent the yoke 88 from being withdrawn or moved along the time set shaft 33 unless it is rotated manually sufficiently far so that the lug 107 clears the shading ring 66.

The side movement limiting section 105 performs an important function in the operation of the hammer 87. It is relatively long and narrow and is sufficiently resilient so that, on striking the surface of the motor frame 67 it causes the yoke 88 and therewith the hammer 87 to rebound and, assisted by the force imparted by the cam 51, the latter to impact the bell 82 with a sharp blow and to produce a clear ringing tone.

Integrally formed with the yoke 88 is a cut-out arm 108 which serves to position either automatically or manually the yoke 88 in either the operative or the non-operative position. The cut-out arm 108 is arranged to be engaged by a rearwardly turned end 109 of an alarm cut-off 110, the end portion 109 projecting through an aperture 111 in the base plate 71 so as to register with the cut-out arm 108 external thereto. The alarm cut-off lever is rockably mounted at 112 inside of the cup-shaped base plate 71 and it has a hook portion 113 to which a coil tension spring 114 is secured, the other end being fastened to a lug or tab 115 that may be struck up from a top plate 116, Figure 7, which, as is more fully described in Gallagher Patent No. 2,491,108, issued December 13, 1949, is located underneath the face 14 and closes the front side of the base plate 71.

The position of the alarm cut-off lever 110 is controlled in part by an inclined surface or edge 117 of an upturned end portion 118 of an alarm release lever 119. This is shown more clearly in Figures 6 and 8 of the drawings. As there shown and also as illustrated in Figures 7 and 9, the inclined surface 117 engages an adjacent edge of an arm 110' that is integrally formed with the cut-off lever 110 so that, depending upon the point engagement, the cut-off lever 110 either

occupies the position shown in Figure 6 when the alarm is released or the position shown in Figure 8 when the alarm has been shut off.

The alarm release lever 119 has at the end opposite the section 118 a pair of up-turned bearing sections 120 which are slotted their full length so as to interfit with a shaft 121 that is journaled in lugs 122 that are struck up from the top plate 116. The intermediate portion 123 of the alarm release lever 119 is of a generally U-shape and interfits with an alarm set sleeve 124 that is slidably mounted on the sleeve 25 which supports the hour hand 17.

The sleeve 124 has integrally formed top and bottom flanges 125 and 126. The bottom flange 126 contains a V-shaped notch 127 with which a detent 128, struck up from the alarm set gear wheel 57 cooperates. It will be recalled that the position of the alarm set gear wheel 57, and thereby the position of the detent 128, may be set by the alarm set knob 61 to a position corresponding to the time, as indicated by the alarm set hand 18, that it is desired that the alarm be sounded. The alarm set sleeve 124 is driven by the gear wheel 27 by a slideable connection which comprises a slot 129 in the upper flange 125 and a detent 130 which extends into the same and is integrally formed with the gear wheel 27. Thus the alarm set sleeve 124 rotates conjointly with the gear wheel 27 and it rides on the upper edge of the detent 128 until the notch 127 is brought into register therewith as illustrated in Figure 7. Thereupon the alarm set sleeve 124 slides along the sleeve 25. This movement is caused by a coil tension spring 134, Figures 6 and 8, one end of which is secured to a hook portion 135 of the alarm release lever 119 and the other end is secured to a tab 136 which is struck up from the top plate 116.

During the period when the alarm is not in operation and while the alarm set sleeve 124 is traveling toward the alarm release position, the alarm set sleeve 124 is spaced away from the alarm set gear wheel 57 toward the gear wheel 27 as viewed in Figure 9. During this interval the inclined surface 117 cooperates with the arm 110' to hold the alarm cut-off lever 110 in the position shown in Figure 8 where the yoke 88 is held in inoperative position between the bell 82 and the cam 51. When the notch 127 is moved so that it registers with the detent 128, as illustrated in Figure 7, the inclined surface 117 is moved toward the top plate 116 by the coil tension spring 134 and it no longer interferes with the movement of the alarm cut-off lever 110. Its spring 114 then rocks the same to the position shown in Figure 6 whereupon the yoke 88 can be rocked by the cam 51 to cause the hammer 87 to strike the bell 82 as described hereinbefore.

In order to manually control the release of the alarm and to shut it off soon after it starts to operate, an alarm release knob, shown generally at 137 in Figure 12, is provided. The alarm release knob 137 includes a knob portion 138 which projects through the back plate 75 and which can be grasped by the thumb and forefinger to pull the same out for releasing the alarm or pushing the same in to shut it off. At its inner end the alarm release knob 137 has a twisted portion 139 which interfits with a slot 140 in the base plate 71, Figures 6 and 8, to cause the knob 137 to rotate slightly when it is pulled out or pushed in. An arm 141 extending from the alarm release knob 137 is arranged to cooperate with the side of the end portion 109 of the cut-

off lever 110 that projects through the aperture 111 for holding the same and thereby the cut-out arm 108 of the yoke 88 in the alarm cut-off position as viewed in Figure 4. The knob 137 has a hook portion 142 to which a coil tension spring 143 may be secured. The other end of the spring 143 may be fastened to one of the pillars 74, as indicated in Figures 6 and 8.

As long as the alarm release knob 137 is pushed in the arm 141 thereof holds the cut-off lever 110 in the position illustrated in Figure 4 of the drawings. Even though the alarm set sleeve 124 is rotated to the position shown in Figure 7, the alarm will not be sounded. However, when the alarm set knob 137 has been pulled out so that the arm 141 occupies the position as shown in Figures 3, 6 and 8 of the drawings, the alarm will be operated as soon as the alarm set sleeve 124 is rotated to the position shown in Figure 7 of the drawings.

The hammer 87 is illustrated in Figures 4 and 8 of the drawings in the inoperative position. In Figure 4 the alarm set knob is in the "off" position so that the hammer 87 cannot be operated by the cam 51 at any time. The alarm set knob 137 is in the "on" position in Figure 8 and the hammer 87 can be operated by the cam 51 to strike the bell 82 when the notch 127 in the sleeve 124 registers with the detent 128 at the time the alarm is set to operate.

In such inoperative position of the hammer 87, provision can be made for having the tip 86 thereof bear against the bell 82 under a slight thrust exerted by the resilient cut-off arm 108. For this purpose the alarm cut-off lever 110 and its end portion 109 in the alarm "off" position can be so located that the hammer 87 is maintained in engagement with the bell 82, with the cut-out arm 108 deflected downwardly slightly, thereby resiliently maintaining the desired engagement. Thus, the hammer 87 can be prevented from moving and striking the bell 82 while the clock is being handled.

Since certain further changes can be made in the foregoing construction and different embodiments of the invention can be made without departing from the spirit or scope thereof, it is intended that all matter shown in the accompanying drawings or described hereinbefore shall be interpreted as illustrative and not in a limiting sense.

I claim as my invention:

1. In an electric alarm clock, in combination, a base plate, a motor mounted on said base plate having a rotor and a frame including a radially projecting flange, an alarm bell mounted on said base plate, a shaft extending from said base plate, a generally U-shaped bell hammer support yoke rockably mounted on said shaft each arm of which is bifurcated, the arm of said yoke adjacent said base plate having a section for engaging said motor frame to limit movement of the yoke away from said bell and another section having a convex surface for engaging the face of said flange adjacent said base plate to prevent removal of the yoke from said shaft, the other arm of said yoke having a hammer supporting section and a cam striking section, a hammer

carried by said hammer supporting section for striking said bell, and a cam driven by said motor for engaging said cam striking section to oscillate said yoke whereby said hammer intermittently strikes said bell.

2. The invention, as set forth in claim 1, wherein the motor drives time indicating means and manually operable means are provided for setting said time indicating means which includes the shaft on which the bell hammer support yoke is mounted.

3. The invention, as set forth in claim 1, wherein the bell hammer support yoke has an integrally formed cutout arm, means cooperating with said cutout arm for holding said yoke and the hammer carried thereby in an inoperative position between the bell and the motor driven cam, and means driven by the motor for releasing said yoke holding means to permit operation of the alarm mechanism.

4. The invention, as set forth in claim 1, wherein the section of the arm of the yoke adjacent the base plate is resilient and springingly engages the motor frame to cause the yoke and thereby the hammer to rebound and to assist the cam in operating the same to strike the bell with a sharp blow.

5. The invention, as set forth in claim 1, wherein the bell hammer support yoke has a resilient cutout arm, means cooperating with said cutout arm for causing the same to hold resiliently said hammer in an inoperative position in engagement with the bell, and means driven by the motor for releasing said yoke holding means to permit operation of the alarm mechanism.

6. In an electric alarm clock, in combination, a synchronous electric motor arranged to drive time indicating means, an alarm bell, a hammer for striking said bell, a cam driven by said motor for operating said hammer, and resilient means operating simultaneously with said cam for causing said hammer to rebound toward said bell at the limit of its movement away from the same.

WILLIAM P. GALLAGHER.
